FIG. 4. INVENTOR.
HERBERT L. TIPPERMAN

BY
Abraham Friedman
Atty.

UNITED STATES PATENT OFFICE

2,607,829

PORTABLE TESTING DEVICE

Herbert L. Tipperman, Brooklyn, N. Y.

Application March 24, 1950, Serial No. 151,683

1 Claim. (Cl. 175—183)

1

This invention relates to a portable electrical testing device adapted to be combined with a flashlight.

It is an object of this invention to provide a testing instrument capable of performing simple, continuity, resistance and voltage tests as a self contained portable device combined with a flashlight and capable of being manufactured simply and economically.

It is a further object of this invention to provide a device of the character indicated wherein means are provided for storing and carrying the test leads used in connection with the performance of the above mentioned tests.

An additional object of this invention is to provide a flashlight with means readily attachable thereto to form part thereof for the purpose of performing a variety of tests, said means being readily interchangeable in order to adapt the device to a variety of testing situations which may be encountered.

Other and further objects of this invention will become apparent from the description thereof contained in the annexed specifications, or will otherwise become obvious. It will be understood that the invention herein disclosed may be employed for other purposes to which the structure and arrangement are adapted.

Figure 1 is an elevational view of the device comprising the present invention partly broken away.

Figure 2 is a cross-section of Figure 1 taken along 2-2.

arrangement showing the test leads plugged into position, and

As shown in Figure 1, the invention comprises a flashlight of substantially conventional construction housed in a cylindrical casing 11 preferably molded or otherwise formed of non-conductive material. Supported at one end of casing 11 is a lens and lamp assembly which may advantageously be detachably secured thereto as by means of threaded collar 12. The lens assembly comprises a lens 13 and a reflector element 14 which is provided with a socket 15 adapted to receive the conventional flashlight type incandescent bulb or lamp 16. Flashlight cells 17 and 18 of conventional type are shown positioned within the casing. The center terminal of the upper cell 17 contacts the center terminal of lamp 16 in conventional manner. The cells are securely held within casing 11 by means

of sleeve 19, as more clearly appears from Figure 4. As shown in said figure, sleeve 19 is provided with an internally threaded portion adapted to be cooperatively engaged with the externally threaded portion of casing 11. Sleeve 19 is additionally provided with a transverse wall 20. Helical spring 21, of conductive material, is interposed between the bottom terminal of cell 18 and wall 20, thereby resiliently urging the cells into contact with each other as well as with the center terminal of lamp 16. The lowest convolution of spring 21 contacts conductor 22 and completes the electrical circuit to one terminal of switch 23. Switch 23 is of conventional type and is provided with a slide element 24 which selectively completes or interrupts the conductive path between conductors 22 and 25. The latter conductor is electrically connected to the screw threaded portion of the lamp socket carried by reflector 14 thereby completing the circuit from the base of cell 18 to the outside or screw terminal of the lamp. The flashlight operates in conventional manner; the lamp thereof being illuminated upon the closing of switch 23 to complete the circuit.

Jacks 26 and 27 which may advantageously be of the pin type are provided in physical abutment with the end portions of conductors 22 and 25 thereby making electrical contact with each of them. The jacks extend through the switch housing and open to the exterior of casing 11, thus providing means for making electrical contact with the ends of said conductors externally of the casing. The electrical contact is made by means of test leads 28 which are provided with plugs adapted to be inserted into said jacks. Figure 3 is a fragmentary view of the switch portion of the casing and shows test leads 28 plugged into position in said pin jacks.

40 When switch 23 is in open condition and the test leads are plugged into said jacks, the flashlight lamp will be illuminated upon the completion of the electrical circuit through the test prod ends of the test leads. Thus the electrical continuity of any device such as a fuse or that of a circuit may be readily tested. An indication of resistance, in low resistance circuits, may also be obtained by noting the degree of illumination of the lamp.

45

50 The location of the jacks is such that normal
55 flashlight construction and switching arrangement
may be utilized, the switch housing being
advantageously utilized for this purpose. Although it has been found convenient to utilize
independent jacks for the purpose of receiving

the test lead plugs; such jacks may be eliminated and perforations drilled or formed in the non-conductive material of the casing. The perforations are formed in the same location as the jacks. In the event that such perforations are utilized the plugs when inserted abut directly against conductors 22 and 25 thereby making electrical contact with each of them. The use of said perforations accomplishes a result similar to that achieved by the jacks but in a more economical manner in the elimination of the cost and assembly of the additional elements.

As shown in Figure 4, the bottom closure for casing 11 is comprised of the assembly formed by sleeve 19 and end cap 29. The sleeve and end cap are formed of a material similar to that of the casing. One end of sleeve 19 is threadedly engaged with the bottom end of casing 11; the other end of said sleeve being threadedly engaged with end cap 29. Sleeve 19 is also provided with transverse wall 20. As more clearly appears from Figure 2, end cap 29 is provided with jacks 30, 31 and 32. The jacks are adapted to receive and make electrical contact with the plugs formed on the ends of test leads 28. Test lamps 33 and 34 are suitably secured within end cap 29 as shown diagrammatically in Figure 2. The test lamps may be of varying voltages such as six, twelve, twenty-four or one hundred and ten volts of conventional filamentary type or one of said lamps may be of neon type. It has been found advantageous to use one six volt filament type lamp in combination with a neon bulb for general electrical testing purposes.

The combination of lamps may be varied in accordance with the general character of the tests for which the device is intended to be used. The lamps may be mounted in the end cap by the use of lamp sockets so as to permit their ready replacement or the lamp terminals may be soldered directly to the leads connecting to the jacks. In the event of the use of a neon bulb a suitable resistor may be inserted in series therewith. The lamps are suited for voltage tests.

One of the terminals of each of said lamps is independently connected to jacks 30 and 32. The remaining terminals of said lamps being connected in common to jack 31. In this manner the selection of an appropriate lamp for a particular test is made possible with the use of a minimum number of jacks. Either lamp may be selected for a test by plugging the test leads into the combination of jacks 30 and 31 or jacks 31 and 32. It will be understood that a greater number of lamps with associated jacks may be utilized if desired. Perforations 35 are provided in the bottom wall of end cap 29 for the purpose of making the condition of illumination of the lamps visible during a test.

It will be noted that by reason of the arrangement herein provided the transverse wall 20 in sleeve 19 sets off a compartment within sleeve 19. This compartment forms a storage space for the purpose of receiving and storing test lead 28 when not in use as more clearly appears in Figure 4. By reason of this arrangement the entire testing device and equipment is self contained and

may be readily and conveniently transported intact. The sleeve and end cap arrangement is adapted to be secured to flashlight of similar construction which are adapted to cooperate with screw threaded portion of the sleeve.

It should be noted that test lamps 33 and 34 may each be inserted in series circuit with the batteries of the flashlight when desired by plugging a test lead across from jack 31 to jack 26 and then utilizing jack 27 in cooperation with either jack 30 or 32 for the purpose of receiving the test leads to be connected to the circuit of device under test.

I have here shown and described a preferred embodiment of my invention. It will be apparent, however, that this invention is not limited to this embodiment and thus many changes, additions and modifications can be made in connection therewith without departing from the spirit and scope of the invention as herein disclosed and hereinafter claimed.

I claim:

An electrical testing device comprising, a flashlight including a casing adapted to receive one or more electrical cells, a switch and a housing therefor formed of insulating material on said casing, conductors connected to said switch, one of said conductors being connected to a cell terminal, an incandescent lamp supported at one end of said casing and connected with the opposing terminal of a cell as well as with the other of said conductors, apertures formed in the switch housing adjacent to said conductors, said apertures being adapted to detachably receive the ends of conducting testing elements and to hold said ends in electrical contact with said conductors, a sleeve adapted to have one of its ends secured to the other end of said casing, a transverse wall formed in said sleeve, an end cap adapted to be detachably secured to the other end of said sleeve to form a compartment therewith adapted to receive and store said testing elements, testing lamps secured within said compartment, electrical receptacles formed in one of the walls of said compartment adapted to detachably receive the ends of said conducting testing elements, apertures formed in one of the walls of said compartment to permit said lamps to be viewed from the exterior thereof.

HERBERT L. TIPPERMAN.
